UNITED STATES PATENT OFFICE.

JAMES H. SPENCER AND JOHN SIMPSON, OF SALINA, KANSAS.

LIFTING DEVICE.

980,020.

Specification of Letters Patent. Patented Dec. 27, 1910.

Application filed October 13, 1909. Serial No. 522,389.

To all whom it may concern:

Be it known that we, JAMES H. SPENCER and JOHN SIMPSON, citizens of the United States, and residents of Salina, in the county 5 of Saline, State of Kansas, have invented certain new and useful Improvements in Lifting Devices, of which the following is a specification.

Our invention is an improvement in lifting 10 devices, and consists in certain novel constructions and combinations of parts hereinafter described and claimed.

The object of the invention is to produce a device especially adapted for lifting forms 15 in reinforced concrete construction, and which will indicate the extent of the lift.

Referring to the drawings forming a part 20 hereof: Figure 1 is a vertical section of the improvement; Fig. 2 is a front view; Fig. 3 is a section on the line 3—3 of Fig. 1; Fig. 4 is a section on the line 4—4 of Fig. 2; and Figs. 5 and 6 are sections on the lines 5—5 and 6—6, respectively, of Fig. 1.

In the embodiment of the invention shown 25 in the drawings the form consists of a frame composed of T-shaped side bars which are connected near their tops by blocks 2, the said blocks being supported by angle brackets 3, which are arranged above and below 30 the blocks at each end, as shown in Fig. 2, and secured to the side bars by rivets or bolts 4. Above and below the blocks 2 the side bars are connected by bolts 5, which extend through openings in the side bars, 35 and are engaged by nuts 6, the blocks acting as spacing blocks to retain the side bars in spaced relation. The plates 7 composing the form are connected to the side members in any suitable or desired manner. The concrete 8 is placed in the forms in any suitable manner after the reinforcing rods 8^a have been placed, and the lifting mechanism to be described is supported on the blocks and engages the rods to lift the forms and to 40 support the forms while the concrete is being placed. The said mechanism comprises a pipe 9, which fits slidably on the rod, and the pipe is graduated, as shown at 10, as is also the rod, as shown at 11. The pipe is 45 connected to the lower block by means of an eye 12, which encircles the pipe, and is provided with a threaded stem 13 passing through the block and engaged by a nut 14.

A plate 15 is connected to the upper block 50 by means of bolts 16 which extend through the said block, and the plate is provided

with spaced depending lugs 17, between which is journaled a dog 18, whose one end is provided with an opening 19 through which the pipe extends, while the other is 60 forked, as shown at 20. The pipe passes loosely through the opening, but when the dog is rocked as shown in Fig. 1 the edges of the opening grip the pipe. A finger or indicator 21 is secured to the upper block by 65 one of the bolts 16, and co-operates with the graduations on the pipe.

A lever 22 is pivoted between the lugs 17 below the lever 18, and the said lever is provided with a socket 23 for receiving a bar. 70 A pair of links 24 are pivoted to the lever, one on each side thereof, by a pin 25, and to the lower end of the links is pivoted a lower dog. The lower dog consists of spaced bars 26 arranged outside of the links and pivotally connected thereto by a pin 27, and on each side of the pipe is arranged a gripping jaw 28 and 29. The jaw 28 is concaved from side to side, as shown at 30 in Fig. 6, and supported by a pin 31, and the jaw 28 is arranged on the pin 27 between the links 24. 80

A weight 32 in the shape of a roller is journaled between the ends of the bars 26 on a bolt 33, the weight acting to normally retain the bars in the position shown in Fig. 1. The upper end of the pipe 9 is threaded, as at 34, and a sleeve 35 is threaded thereon, and two set-screws 36 are threaded through the sleeve into engagement with the rod. 85

A dog 37 is pivoted in a slot 38 of the 90 sleeve on a pin 39, and the inner end of the dog is cam-shaped, as shown at 40, so that when the dog is in the position shown in Fig. 1 the rod is firmly gripped between the dog and the set-screws. The pipe is slidable 95 on the rod, and by adjusting the set-screws 36 the pipe may be used on smaller rods.

In operation the lifting devices are arranged at suitable intervals, and the form is leveled by means of the said devices, and when leveled it is locked in place. When the form is to be lifted the lever 22 is lifted as indicated in Fig. 1. The lifting of the lever moves the bars 26 into substantially horizontal position, thus releasing the gripping jaws. The upward movement of the lever does not offset the dog 18, the lever passing between the arms of the fork, and the said dog holds the load until the lever is again lowered. The bars 26 have, however, moved upward and grip the pipe at a higher point. As the lever moves downward the 100 105 110

frame is moved upward with the links as a swinging fulcrum. When the frame reaches the top of the pipe the pipe may be moved upward by loosening the dog, and when adjusted to proper height the dog is swung downward to lock the pipe in place. The form may be made of any convenient length and by operating the lifting devices in unison it may be lifted bodily until the top 10 of the reinforcing framework is reached.

We claim:

1. A form composed of spaced parallel side bars, bolts connecting the bars, upper and lower blocks between the bars for retaining them in spaced relation, a pipe adapted to encircle a reinforcing rod and slidably supported on the blocks, a sleeve threaded onto the top of the pipe, a dog pivoted on the sleeve for engaging the rod, set-screws threaded through the sleeve for engaging the rod, a dog pivoted to the upper block and having an opening through which the pipe passes, a pair of bars adjacent to the lower block and between which the pipe passes, oppositely arranged gripping jaws on the bars, a weight on the bars for swinging the same to retain the jaws in gripping position, a lever pivoted to the upper block, and links connecting said lever 30 to the bars.

2. A device of the character specified, comprising a frame for connection with the mold, said frame comprising connected spaced side bars, and end bars, a pipe slidably mounted on the frame and adapted to receive a reinforcing rod, means for locking the pipe on the rod, said means comprising a sleeve on the pipe, set-screws threaded through the sleeve for engaging the rod, a lever pivoted to the sleeve and having a cam 40 end for engaging the rod, an upper dog for detachably locking the frame to the pipe, a lower dog having spaced gripping jaws for engaging the pipe, a lever pivoted to the frame, and a connection between the lever 45 and the jaws for releasing the same when the lever is lifted.

3. A device of the character specified, comprising a frame for connection with the mold, a pipe adapted to receive and slide 50 upon a reinforcing rod, means at the top of the pipe for locking the said pipe to the rod, and upper and lower dogs pivoted on the frame and normally engaging the pipe.

JAMES H. SPENCER.
JOHN SIMPSON.
